UNITED STATES PATENT OFFICE.

EDUARD MERTENS, OF GROSS-LICHTERFELDE, NEAR BERLIN, GERMANY.

COMBINATION OF LINE AND SCREEN PHOTOGRAPHY.

No. 874,222.

Specification of Letters Patent.

Patented Dec. 17, 1907.

Application filed July 12, 1906. Serial No. 325,940.

To all whom it may concern:

Be it known that I, EDUARD MERTENS, a subject of the King of Prussia, residing at and whose post-office address is Gross-Lichterfelde, near Berlin, 36 Jägerstrasse, Prussia, Germany, have invented certain new and useful Improvements in the Combination of Line and Screen Photography.

The object of this invention is to provide a process whereby one may produce on a single sensitized surface, combined whole tone and half tone images.

My invention is as follows:—The object to be photographed is separately drawn, printed or otherwise represented on a ground colored black, red, yellow, or green, or a mixture of these colors, one representation being of the whole tones, another representation being of the half tones. These representations are photographed on the same sensitized surface successively in either order, the whole tone representation being obtained without and the half tone with a screen interposed.

Illustrating this process, suppose the object to be photographed consists of a drawing of flowers executed in black-gray-white half tones on a white ground, which is surrounded by a pen-drawing executed with black ink, or by printed text. First, a negative copy of the flowers or the model, in so far as it comprises half tones, is transferred to a black ground, and then the pen drawing is introduced in a light color, for instance, white or blue, on a second black sheet. The negative copy may consist, for example, of an ink-drawing, which in white or blue color consists of light values, which are the opposite of those which the photographic plate is to show. Therefore, in this drawing, that will appear white or blue which in the original or in the negative must be black, and that which is to be light gray in the negative, will here be dark gray or dark blue. The first copy is now photographed with the interpolation of a screen. The objective is then closed, and the second copy, *i. e.* the line drawing is substituted, and this is now photographed on the same plate after the screen has been removed. In this manner, on a

single plate, a positive photographic image is produced in which the half-tones are broken up by screen, while the whole-tones are not broken up. It is evident that while the back-ground of the object is light, or a light surrounds the picture, the background would be photographed and this would make it im-

possible to photograph several copies one over the other. Unless the background is dark, red, yellow or green, or a mixture of these colors, the present form of the invention could not be carried out. The work may be facilitated by using transparent films for making the negatively drawn representations, the films being colored with the above-named non-actinic colors. The films may be translucent, but in such case, when the photograph is to be taken, they must be laid on a black ground, or one which is colored with the above-named non-actinic colors. The latter method offers the advantage that models which are drawn black on white can be traced in white or blue color onto the transparent films, by means of register-crosses, which have previously been marked on the original drawing. Before photographing, the various films are then fastened, cross upon cross, upon the support and then, as the successive films are photographed, only one film after the other need be removed.

Instead of re-drawing the flower and pen-drawing on a black ground, negative representations produced by mechanical means might also be used, which negatives are either photographed by permitting a light ground to shine through, or are illuminated at their transparent places. Here, too, light or transparent half-tone images, as well as line drawings, are photographed one after the other, on the same sensitized plate, each by itself, with a border non-transparent toned with a color chemically inactive during photographing.

The process forming the basis of this application makes it possible also to break up individual portions of the flowers or of the leaves by different screens, by taking not only two consecutive photographs on the same plate, as above described, but three or more photographs. For this purpose, for example, on photographing the one half-tone model a cross-screen is used; on photographing the second half-tone drawing, which for instance may form a part of the flower above referred to, a line screen, so that by changing the screens, or diaphragms, various screen structures may be effected beside each other. When making photogravure films for use on producing fabric printing rollers, the process permits the breaking up of the various parts of the design, according to need, into numerous lineations by inserting various hatching screens, and at the same time combining the

outlines and line drawings with the hatching lines, by successive photographing, onto one plate or film.

In the above described process it is permissible, though not always advantageous, to take two whole-tone and half-tone drawings, mounted exactly one over the other, and belonging to the same design, of which the under drawing is drawn on a dark ground, 10 while the upper drawing must be drawn on a translucent film, and first to photograph these simultaneously, with the interposition of a screen, and then to photograph the line drawing again, alone, without screen.

15 Instead of effecting the combination of screen image and whole-tone image on one plate by process of photographing, it may of course be done also by successive copies and interposition of thin screen films. But the 20 first method will have to be employed in all cases, in which the reproduction is to be of different size from the original, and where an advantage may be obtained by breaking up the image by screen, objective and various 25 diaphragms. These processes may also be successfully used for the so-called gigantography.

The photographic apparatus necessary for taking the photographs may differ from the 30 photographic apparatus hitherto suited to half-tone photographing only in this that one of several screens, during the exposure or the interrupted exposures, can be easily inserted and taken out, or changed, as far as possible 35 without opening the camera, and as far as possible in such manner that this change may be effected from the outside.

One form of the contrivances for inserting 40 and taking out screens, suited to carrying out the process, would for instance consist in this that in the interior of the photographic camera, or on the plate-holder, hinges are affixed, to which the frames of the screens are fastened in such manner that the same may be opened, 45 door-like, into the camera, that is toward the objective, so that, on taking out, one or several screens come to lie against the side of the camera or the bellows, giving a free field of sight while during a screen-exposure the 50 screen in question is set parallel to the plate. So, also, the inserting and taking out could be effected from the outside in such a way that the screens or their frames are slid into the camera or plate-holder, and drawn out, 55 from one or several slides, in the same manner as the slide of a plate-holder.

The process is illustrated in simple form in the accompanying drawings in which

Figure 1 shows the full tones of a clover

leaf; Fig. 2 shows the half tone portions of 60 the leaf; Fig. 2^a, shows the image resulting on the negative after exposure for the half tones; Fig. 3 shows the two images shown in Figs. 1 and 2 arranged before the camera; Fig. 4 shows the completed picture upon the 65 sensitive film; Figs. 5, 6 and 7 show the different petals of the leaf separately drawn to secure the different half-tones shown in Fig 8; Fig. 9 shows these separate sheets arranged before the camera for photography; 70 and Fig. 10 is a cross section of a camera showing an arrangement of the line screens within the same.

It will be seen in Figs. 1 to 4 that the full tone image *a* is arranged behind the half 75 tone image *b* so that upon the first exposure of the film through the screen the image *b*, Fig. 2^a is produced. Upon removing the screen and the half tone image from in front of the camera and again exposing the film, 80 the full tone image *a*, which has been arranged at the start in exact coincidence with the half tone image *b* by means of the cross marks shown, is received by the film, with the result that the completed image in Fig. 85 4 is secured.

In Figs. 5 to 9 is represented the method of procedure where different tones for the different petals of the leaf are attained by exposure through different screens respectively.

The hinging of the screens *f*, *g* and *h* at *f*¹, *g*¹ and *h*¹ within the camera is shown in Fig. 10.

I claim as my invention:

1. The herein described process of producing photographic images, consisting in producing whole-tones and half-tones, first one and then the other, on the same sensitized surface.

2. The herein described process of producing photographic images, consisting in successively exposing to the same sensitized surface whole-tone and half-tone images on grounds of non-actinic color.

3. The herein described process of producing photographic images, consisting in producing successively on a single sensitized surface whole and half-tone photographic images from images on transparent films of 110 non-actinic color.

In testimony whereof I have signed my name to this specification, in the presence of two subscribing witnesses.

EDUARD MERTENS.
